UNITED STATES PATENT OFFICE.

MAURICE DELAPORTE, OF PARIS, FRANCE.

DEVICE FOR INSURING STABILITY OF WORKING OF STEAM-EJECTORS ARRANGED IN SERIES.

1,306,414.

Specification of Letters Patent. Patented June 10, 1919.

Application filed February 17, 1914. Serial No. 819,253.

To all whom it may concern:

Be it known that I, MAURICE DELAPORTE, a citizen of the French Republic, residing at Paris, Republic of France, have invented 5 certain new and useful Improvements in Devices for Insuring Stability of Working of Steam-Ejectors Arranged in Series, of which the following is a specification.

Devices are known which are used as air 10 pumps for extracting air from a steam condenser, and which comprise in combination steam ejectors arranged in series and used with one or more intermediate auxiliary condensers.

15 Devices of the character hereinbefore referred to could not hitherto be successfully employed in practice, either because the apparatus employed were not sufficiently powerful relatively to their consumption of 20 steam, or because the working of the apparatus became unstable when the proper air pressure decreased in the condenser upon which they were working.

The object of the present invention is to 25 provide means, the addition of which has the effect of rendering the working of the arrangement of steam ejectors in series used with one or more intermediate auxiliary condensers perfectly stable, however low the

30 proper air pressure in the condenser may be. The stability of the apparatus being thus obtained under all circumstances, ejectors may be selected the working diagrams of which show the best efficiency relatively to 35 the consumption of steam. The arrangement according to the present invention permits of obtaining an air pump, the working of which is certain and very economical.

Experiments carried out by the applicant 40 have shown that when an ejector is suitably dimensioned so as to effect under the best conditions the extraction of a substantial quantity of gas contained in a receptacle, its operation becomes unstable when the 45 quantity of gas that it draws is greatly decreased. The experiments have shown that in a device comprising two ejectors in series used with an intermediate auxiliary condenser, the whole working upon a steam con-

50 denser under the usual conditions, the working of the first ejector is by itself always stable. This is due to the fact that a system of two steam ejectors in series permits of realizing the theoretical vacuum correspond- 55 ing to the usual temperatures of condensers,

and that consequently the volume of gas drawn by the first ejector is never limited, since in the case of lack of air in the condenser, the water supplies under the form of steam the required volume of gas. 60

This, however, is not the case so far as the second ejector is concerned which can receive only the gases coming from the first ejector; if at any given moment these gases are almost solely constituted by steam, the 65 latter will be condensed in the intermediate auxiliary condenser, so that the amount of gas reaching the second ejector will almost be *nil*. It will thus be seen that if an air extracting device of the kind hitherto proposed operates upon a condenser in which the supply of air is varied, the vacuum increases, thereupon becoming unstable, when the quantity of air supplied is gradually decreased. 70

This instability may be overcome by a surplus in the supply of working steam to the second ejector. This, however, leads to an increase in the expenditure of working steam, and, according to the experiments 80 which have been carried out, it decreases the extracting power of the apparatus, so that the working thereof under these conditions is not economical.

The cause of the instability may also be 85 overcome by effecting a permanent admission of air to the condenser; such an arrangement, however, is defective since it causes a drop in the vacuum of the condenser relatively to the obtainable theoretical 90 vacuum, the amount of this drop being directly proportional to the amount of air that has been admitted.

The invention consists in the addition to the known arrangement of steam ejectors 95 in series used with an intermediate auxiliary condenser, of means which will allow the introduction of a supplementary amount of gaseous fluid into the gaseous mixture extracted from the condenser, the introduction 100 of the said gaseous fluid being effected after the gaseous mixture referred to has already been subjected to a certain amount of compression in the first ejector.

Figures 1, 2, and 3 in the accompanying 105 drawings illustrate by way of example three different ways of carrying the invention into effect:—

Referring to the arrangement illustrated in Fig. 1, *a* is the main condenser which is 110

preferably shown as a jet condenser, the steam to be condensed entering therein at *b*; *c* is a tank containing the cooling water which is raised into the condenser through 5 the pipe *4* under the action of atmospheric pressure; *d* is a centrifugal pump by which the water of condensation is drawn from the lower part of the main condenser and delivered to the hot-water tank *e*. The gaseous 10 mixture from the main condenser is drawn through a pipe *f* which communicates with two ejectors, a first ejector *g* and a second ejector *h*, which are arranged in series with each other and which are fed with steam 15 through a pipe *k*. A small auxiliary condenser *i* which is preferably of the injection type is preferably interposed between the two steam ejectors, its lower end being connected with the main condenser *a* by means 20 of a siphon *m*, the injection water being supplied at the upper end thereof through a pipe *n* connected with the pipe *4*; the second ejector *h* communicates with the atmosphere through a pipe *o*. Upon the suction chamber 25 of the second ejector *h* is arranged a stopper *p* provided with holes 5 capable of being covered and uncovered by a movable plate *q*, to any desired extent. According to the position of the latter plate the quantity 30 of air sucked into the system is varied between any desired limits the additional air mixing with the gaseous mixture coming from the main condenser *a*. A tap, cock, or other air valve may be used instead of the 35 stopper *p*.

In the arrangement illustrated in Fig. 2, the stopper *p* is replaced by a valve *s* which is arranged to work automatically. This valve is spring controlled, the tension of the 40 spring *r* being regulated in such a manner that when the pressure exerted on the upper part of the valve *s* decreases below a certain value, air is sucked into the plant through the openings *t*, which air mixes with the 45 gaseous fluid extracted from the main condenser *a*.

It is not absolutely necessary that the supplementary gaseous fluid shall be air, as any other gaseous fluid may be used instead, for 50 instance, additional steam may be employed, in which case, the steam should be added beyond the auxiliary condenser, so that this steam shall reach the second ejector without fail.

55 Referring to the arrangement illustrated in Fig. 3, the valve *s* is arranged to admit an additional supply of steam, such steam being drawn from the outlet of the first ejector, which in this case must be sufficiently powerful to supply the necessary quantity of steam therefor. The variation of the pressures on the two sides of the valve *s* is very small. The lower end of the stem *u* which is of substantial thickness and is maintained on 60 its seat by a spring *r* is under the action of

atmospheric pressure. It will thus be seen that when the pressure exerted on the upper side of the valve decreases below the value for which the spring *r* is adjusted, the valve will lift and allow the steam coming from 70 the first ejector, and which is not condensed as it does not pass through the auxiliary condenser *i*, to enter into the second ejector, and mix with the gaseous fluid extracted from the condenser *a*.

75 It is to be understood that the shape of the means provided for the admission of additional gaseous fluid, shown in Figs. 1, 2 and 3, by way of example, may be varied.

The additional air or steam may be derived from any source, provided it comes from a medium in which the pressure is higher than that existing in the described apparatus, at the point of introduction. Thus, the air need not come directly from 80 the atmosphere, but from a receptacle in which it is desired to maintain a decreased vacuum, and the steam may be derived from another source than from the outlet of the first ejector. However, in no case can the 85 gaseous fluid be derived from the condenser from which the first ejector draws, as its addition must be effected in a region of the apparatus where the pressure is higher than that existing in the condenser.

90 The additional gaseous mass, which in order not to have a disadvantageous effect upon the vacuum of the condenser must be introduced in a region where the mixture extracted from the condenser has already been 100 subjected to a certain amount of compression, exerts its stabilizing action by completing the volume of gas which is required in order that the ejected stream shall during its passage fill up the neck, viz., the part of 105 reduced section of the second ejector. It thus follows that the region of introduction of the supplementary mass of gas may be chosen at will between the end of the jet nozzle which supplies the first ejector with 110 working steam and the neck of the second ejector.

The arrangement comprising two steam ejectors in series, an intermediate auxiliary condenser, and means for the addition of a 115 supplementary amount of gaseous fluid, which means form the object of the present invention, may be combined with other ejectors, other auxiliary condensers, and be employed together in the form of a more complex plant.

120 The extracting devices hereinbefore referred to may be employed for extracting gases from a steam condenser, or from any other receptacle.

125 What I claim is:—

1. A plant for extracting gases from a receptacle, comprising in combination with a first and a second steam ejector arranged in series with each other and an intermediate 130

auxiliary condenser, additional means for increasing the mass of gas delivered to the second ejector, the inlet of the said means for introducing the supplementary amount 5 of gaseous fluid necessary for this increase being situated at a point where the gases extracted from the receptacle have already been subjected to a certain amount of compression.

10 2. A plant for extracting gases from a receptacle comprising in combination with a first and a second steam ejector arranged in series with each other and an intermediate auxiliary condenser, a member for the automatic 15 admission of supplementary gaseous fluid, in order to increase the gaseous mass delivered to the second ejector, the inlet of the said member for introducing the supplementary amount of gaseous fluid necessary 20 for this increase being situated at a point where the gases extracted from the receptacle have already been subjected to a certain amount of compression.

3. A condensation plant, comprising in 25 combination with a condenser and an air extracting device consisting of a first and a second steam ejector arranged in series with each other and an intermediate auxiliary condenser, means added to said air extracting device for increasing the gaseous mass 30

supplied to the second ejector, the inlet of the said means for introducing the supplementary amount of gaseous fluid necessary for this increase being situated at a point where the gases extracted from the receptacle have already been subjected to a certain amount of compression. 35

4. A condensation plant comprising in combination with a condenser and an air extracting device consisting of a first and 40 a second steam ejector arranged in series with each other and an intermediate auxiliary condenser, a member added to the said air extracting device for automatically admitting a supplementary amount of gaseous fluid, in order to increase the gaseous mass supplied to the second ejector, the inlet of the said member for introducing the supplementary amount of gaseous fluid necessary for this increase being situated at a 45 point where the gases extracted from the receptacle have already been subjected to a certain amount of compression. 50

In witness whereof I have hereunto set my hand in the presence of two witnesses.
